ELEVATED RAILWAY.

No. 529,757.

Patented Nov. 27, 1894.

UNITED STATES PATENT OFFICE.

THOMAS J. SHORB, OF CAPE GIRARDEAU, MISSOURI.

ELEVATED RAILWAY.

SPECIFICATION forming part of Letters Patent No. 529,757, dated November 27, 1894.

Application filed February 21, 1893. Serial No. 463,163. (No model.)

To all whom it may concern:

Be it known that I, THOMAS J. SHORB, of the city of Cape Girardeau, Cape Girardeau county, and State of Missouri, have invented 5 certain new and useful Improvements in Elevated Railways, of which the following is a full, clear, and exact description, reference being had to the accompanying drawings, forming a part hereof.

10 My invention relates to improvements in "elevated railways," and consists in the novel arrangement and combination of parts, as will be more fully hereinafter described and designated in the claims.

15 The principle involved in my invention is that of suspending the car below the super-structure, having the traction-wheels located above the center of gravity and providing certain parts for guiding and controlling the car.

20 In the drawings: Figure 1 is a side elevation of the super-structure and showing the car suspended therefrom. Fig. 2 is a vertical enlarged sectional view showing the spring controlled hanger for the car. Fig. 3 is a detail side elevation of the trolley and stand. Fig. 4 is a top plan view of the truck and motor geared thereto. Fig. 5 is a side elevation of the superstructure. Fig. 6 is an end sectional view of the superstructure and car.

25 Referring to the drawings: 1 indicates the complete superstructure, a description of which I will first give.

In the accompanying drawings I have shown the superstructure as built for a double-line 30 of railway, although a single super-structure would substantially involve the same construction.

The primary supports consist of three rows 2, 3 and 4 of metallic columns 5, said columns 35 being constructed of any suitable style and of such a construction as involves the necessary braces to assist in the support of the super-structure. Adjoining pairs of columns 5 in each of the rows are connected by arches 6 in the highest portion of which is intermediate 40 of the two columns and connected with the roof-plate 7 by a double T-iron 8. The arch 6 is additionally braced by angle-irons 9 bolted under the roof plate 7 and to the col-

umn 5 and extending therefrom to the arch 50 6, to which the same is also bolted. The three columns 5 in each transverse row are connected by the roof plate 7 as above stated and by upwardly extending angle braces 11, the elbow of which is over the center of each 55 track. Secured to the column 5 and extending inwardly are horizontal braces 12 to which two track-rails 13 are secured, said track-rails thus being located intermediate of the middle row and outside rows of columns 5. The 60 tracks 13 are located a slight distance apart to allow for the passage of the hangers from which the car depends. The braces 12 are additionally secured by angle braces 14 extending downwardly and secured to the columns 5 and by angle-braces 15 extending upwardly and secured to said columns immediately under the roof-plate 7. Further supports are provided by vertical braces 16 which are secured to said braces 15 and to the roof-plate 7 at a point intermediate of a vertical 65 line with the rails 13 and the columns 5. Additional supports for the rail are provided by guy-rods 17 which extend from the angle-braces 11 at equidistant points toward the 70 center of the rail between the two adjoining columns 5, each of said rods 17 being provided with turn-buckles 18 by means of which their length may be adjusted to equalize the 75 height of the track-rails.

80 The arrangement of the guy rods 17 is particularly shown in Figs. 5 and 6 and therefore needs no further and specific description, except that the lower ends of said rods are secured to insulation-blocks 19 in order that 85 the current in the rails will not be carried into the super-structure, that is, in case the road is operated by electricity. In carrying out this feature of the construction I desire to also make mention of the fact that the rails 90 13 are insulated from the braces 12 by plates 20 as shown in Fig. 6. It will thus be seen that the super-structure is especially designed for the supporting of the car below the center of gravity which in this case includes the 95 wheel and trucks operative over and between the rails 13. The wheels made use of have two tread surfaces 21 and an intermediate

annular flange 22 adapted to fit between the two rails 13 and said tread surfaces 21 upon the upper edges of said rails.

As to the particular form of car used, there is no limitation as any suitable style could be used this being determined partly by the motive power used to operate the road.

Secured to the sides of the car and extending over the top of same to a center point are metallic hanger irons 23 additionally braced to the car by projecting angle-braces 24 which extend under and are secured to the under side of the cars, as is also the case with the strip 23.

Extending upwardly from the meeting point 5 of the iron 23 from both sides of the car is a vertical bar 25 in the top of which is transversely located a pin 26, said bar 25 extending upwardly through a casing 27 secured to the under side of the truck-beams 28, which 20 are mounted upon the axles 29 of the friction-rollers or wheels.

The top of the casing 27 has two downwardly and inwardly projecting lugs 30 provided with vertical slots 31 in which the pin 26 has its movement, such movement being controlled by a spring 32 located under said pin and between the same and the lower side of the casing 27. The movement of the car is thus eased and regulated by the spring 32, 30 the function of which is to prevent the rocking of the car. One pair of the friction-rollers is sufficient for an ordinary length of car, and the truck-beams 28 are provided with two or more casings 27, any desirable number of which can be fitted up with the necessary parts and depending hangers to secure the relative location of the car.

The truck beams 28 mounted upon the axles 29 of the friction rollers hold said rollers in their proper alignment and in the accompanying drawings, wherein I have shown electric motor power applied, I have provided bearings for an electric motor 33, the armature shaft 34 of which projects beyond both 45 ends of the coil. Said projecting end of the armature shafts are provided with bevel gears 35 adapted to mesh into bevel gears 36 upon the ends of canted shafts 37, bearings for which are provided by projections 38 outwardly from each of the truck beams 28. The lower ends of the shafts 37 are also provided with bevel gears 39 which mesh into bevel gears 40 upon the projecting ends 41 of the axle upon which the rear traction-roller and 55 the ends of the truck-beams 28 are mounted. This connection between the axle 41 and the motor 33 enables the governing of the speed at which the car is run, by means of the necessary appliances located in the car and connected with said motor. It has not been thought necessary to show the controlling appliances, as one of the principal ideas which I desire to convey is that any motive power in use can be applied to this construction, and

in this connection I desire to reiterate that the principle herein involved is that of depending the ears below the center of gravity and the providing of the necessary super-structure for the carrying out of my invention. In case electricity is used as herein shown, I have provided a trolley-wire 42 held by clamps 43 in alignment above the rails 13, and have also provided feed-wires 44 carried by the super-structure and having branch-wires 45 to conduct the currents into the trolley-wire 42. 75

The trolley 46 has its wheel 47 in normal contact with the trolley-wire 42 and its lower end insulated from connection with the truck by a plate 48 of insulation material located above the trolley-base 49, with wires 50 leading from the trolley 46 to the motor-connection. The opposite pole of the current to that carried by the trolley wire, is distributed into the track-rails 13 and from thence into the traction-rollers to the necessary motor-connection. 85

In order that the cars will maintain a determinate vertical position, I have provided cross-braces 51 secured to the columns 5 and provided to support a longitudinal guide rail 90 52, which is circular in cross-section and adapted to provide side-bearings for rollers 53 secured under the car and upon each side of said guides 52.

I have now specifically described the construction of the super-structure and set forth the principle involved in my invention. It is noticeable that the construction is such as to insure the desired supporting of parts to produce the result contemplated by me in my invention, and particular attention is called to the thoroughness with which I have suspended the car and provided the necessary devices to guard against accidents of any kind. If desirable I could provide a 105 double track for each line of railway, that is, make use of two pairs of track-rails located each side of the center, this construction requiring two tracks and motor connections.

Having fully described my invention, what I claim is—

1. An improved elevated railway having a super-structure comprising a number of upright columns supported by cross braces, said braces securing aligned track-rails, traction rollers having a central annular flange adapted to travel between said rails, the outer tread surfaces of said traction-rollers adapted to engage upon the tops of said adjoining rails, said traction-rollers located relatively above the center of the car, said rollers connected by truck beams, and depending hangers connecting said truck with the car and adapted to depend the same below the center of gravity, substantially as set forth. 120 125

2. An improved elevated railway having a super-structure comprising a number of upright columns connected in rows by arch

braces, connected in parallel by cross-braces, the track-rails held above the surface and between said rows of upright columns, traction-rollers adapted to be operated upon said 5 rail, said traction rollers having two outer tread surfaces, an intermediate annular flange adapted to operate between said track rails, and two of said rollers connected in longi-

tudinal alignment by truck-beams, substantially as set forth.

In testimony whereof I affix my signature in presence of two witnesses.

THOMAS J. SHORB.
